JOSEPH HARRIS, OF CHICAGO, ILLINOIS, ASSIGNOR TO WILLIAM H. MINER, OF CHAZY, NEW YORK.

DRAW-BAR AND YOKE CONNECTION.

1,286,611.

Specification of Letters Patent.

Patented Dec. 3, 1918.

Application filed August 20, 1917. Serial No. 187,208.

To all whom it may concern:

Be it known that I, JOSEPH HARRIS, a citizen of the United States, residing at Chicago, in the county of Cook and State of Illinois, have invented a certain new and useful Improvement in Draw-Bar and Yoke Connections, of which the following is a full, clear, concise, and exact description, reference being had to the accompanying drawings, forming a part of this specification.

This invention relates to improvements in draw bar and yoke connections.

One object of the invention is to provide a detachable draw bar and yoke connection for railway draft riggings which is applicable to yoke straps of the riveted type and all standard types of draw bars regardless of the presence or absence of coupler-key slots therein.

Another and more specific object of the invention is to provide a detachable connection of the type above specified so arranged that the means which directly connect the yoke strap and draw bar are placed under double shear to thereby increase the strength of the detachable connection and to further arrange the connection so that the draw bar can be disconnected from the yoke without disturbing the draft gear.

In the drawing forming a part of this specification, Figure 1 is a part vertical section, part side elevation of a draw bar and yoke showing my improvements in connection therewith. Fig. 2 is a horizontal, sectional view, taken on the line 2—2 of Fig. 1. Fig. 3 is a vertical, sectional view, taken on the line 3—3 of Fig. 1. Fig. 4 is a detail perspective view of the detachable locking block employed with my construction. And Fig. 5 is a view similar to Fig. 1, but illustrating a different embodiment of the invention.

In said drawing, referring to the construction illustrated in Figs. 1 to 4, A designates a standard draw bar; B a U-shaped yoke of the rivet type; C a hollow cast hood or head; D a locking block; and E a retaining key for the block D.

The draw bar A, being of the standard type, is provided with the usual upper and lower shoulders 10 and 11 and upper and lower sets of rivet receiving holes 12 and 13.

The strap B is of the usual U-shape having upper and lower arms 14 and 15, rear

connecting piece 16, filler block 17, and the usual standardly spaced rivet receiving holes 18—18 in the upper arm and corresponding rivet holes 19—19 in the lower arm.

The head C is preferably in the form of a casting, and has upper wall 20, parallel side walls 21—21, lower cross connecting portions 22 and 23, and an upper transverse gib 24 adapted to engage the upper shoulder 10 of the draw bar. On its inner face, the upper wall 20 of the head C is provided with a pair of depending lugs 25—25 adapted to extend through the rivet receiving holes 18 and into the holes 12. The length of the lugs 25 is such that the bottom ends thereof do not extend below the lower face of the gib 24, the reason for which will appear hereinafter.

The block D is of substantially right angular formation having a lower wall 26 and upstanding wall or shoulder 27, the latter being adapted to engage the lower shoulder 11 of the draw bar. The block D is insertable and removable through an opening in the lower part of the hood C and when in position, is adapted to have the shoulder 27 thereof engage at its side edges against side abutments 28—28 formed on the inner faces of the side walls 21. The block D is provided on its upper face with a pair of lugs 29—29 adapted to penetrate the rivet receiving holes 19 and the holes 13 in the draw bar. The block D is held in its operative position by the key E, the latter being supported on top of the cross pieces 22 and 23 and having a depending front portion 30 through which is extended a bolt 31 for retaining it in place.

The distance between the lower face of the gib 24 and the upper surfaces of the cross pieces 22 and 23 is made slightly greater than the height of the draw bar butt plus the thickness of the lower arm of the yoke B. In assembling the parts, the hood C is placed over the ends of the yoke strap and the lugs 25 inserted through the holes 18 of the upper yoke arm. The butt of the draw bar A is then inserted longitudinally within the head C and below the gib 24 and during this movement, the lower arm 15 of the yoke strap is depressed against the upper face of the cross wall 23. The draw bar having been inserted sufficiently, it is then elevated, thus causing the lugs 25 to enter the upper holes 12. The lower arm of

the yoke strap will spring upwardly of its own accord and then the block D may be inserted to the position shown in the drawing and held by the key E.

5 Due to the fact that the hood C and block D each have shouldered engagement with the draw bar, it is obvious that the lugs 25 and 29 are placed under double shear thus providing a very strong connection between 10 the draw bar and yoke strap. With the arrangement shown it is also possible for old yoke straps of the riveted type to be reemployed without modification other than the shearing off of a small section of the strap 15 at the front ends of the arms thereof, thus effecting a large saving for the railroads and at the same time giving a detachable connection between the yoke and the draw bar.

20 In the construction illustrated in Fig. 5, the yoke strap B' and the draw bar A' are the same as shown in the other figures. The hood C' at the top thereof is provided with a gib 124 the same as in the other construction. At the bottom, however, the hood is provided with a substantially solid transverse wall 40 spaced below the gib 124 a distance greater than the height of the draw bar butt plus the thickness of the lower arm 30 of the yoke strap. The block D' is the same as the block D except that it is made somewhat thicker and has a transverse recess 41 therein through which is adapted to extend a key 42, the latter being inserted laterally through suitable perforations 43 in the side walls 121 of the hood C'. The block D' is of right angular formation and has the front shoulder 127 thereof adapted to engage the lower shoulder of the draw bar butt, said block D' being insertible from the front end of the hood instead of through the bottom. The block D' is held in position after it is inserted by a transverse key 42 which passes through a suitable opening in 45 said block and suitable openings 43 in the side walls 121 of the hood C'. To connect the yoke strap B' with the hood, block and draw bar, I employ a pair of vertical bolts 44 which extend through suitable aligned perforations in the upper wall of the hood C', the block D', and the lower wall of the hood C'. The lower wall of the hood C' may be recessed on its under face as indicated at 50 to accommodate the nuts on the bolts. The key 42 may be so positioned as to be held 55 against lateral displacement by the bolts 44, the key being notched, as indicated at 46-46 for this purpose.

With the construction just described, it is 60 obvious that the bolts 44 are placed under double shear both at the top and bottom the same as the integral lugs or the studs illustrated in the other figures.

I claim:

65 1. In a device of the character described,

the combination with a yoke strap and a shouldered draw bar provided with standardly disposed rivet holes; of devices for detachably connecting the strap and draw bar, said devices including a hood, a locking block, the hood and locking block having each transverse shoulders to engage the shoulders of the draw bar, and means penetrating the holes of the yoke strap and those of the draw bar, said means being longitudinally immovable with respect to said hood and block whereby said means are under double shear with respect to each yoke arm. 70

2. In a device of the character described, the combination with a yoke strap and a shouldered draw bar provided with standardly disposed rivet holes; of a hood having a transverse upper shoulder adapted to engage the upper shoulder of the draw bar and the lower wall of which is spaced below 85 said gib a distance equal to at least the height of the draw bar plus the thickness of one arm of the yoke strap; a shouldered locking block insertible beneath the draw bar butt and having shouldered engagement therewith; and means penetrating the rivet holes of the yoke strap and draw bar, said means having engagement with the hood and block outside of the yoke arms. 90

3. In a device of the character described, the combination with a yoke strap and a shouldered draw bar provided with standardly disposed rivet holes; of a hood within which the draw bar butt is received; of a block insertible within the hood; means for 100 engaging the hood and block with the draw bar so that the same are pulled forwardly with the draw bar; and means penetrating the holes of the yoke strap, said means being pulled forwardly by the hood and block at 105 points outside of the yoke strap and by the draw bar butt at points inside of the yoke strap. 95

4. In a device of the character described, the combination with a yoke strap and a 110 shouldered draw bar provided with standardly disposed rivet holes; of devices for detachably connecting the strap and draw bar, said devices including a hood, a locking block, the hood and locking block having each transverse shoulders to engage the shoulders of the draw bar, and means penetrating the holes of the yoke strap and those of the draw bar, said means being longitudinally immovable with respect to said hood and block whereby said means are under double shear with respect to each yoke arm, said means being formed integrally with the hood and block. 115

5. In a draw bar and yoke connection, the 120 combination with a shouldered draw bar and yoke strap having standardly spaced rivet receiving holes therein; of a hollow hood within which is adapted to be received the draw bar butt, said hood having an upper 125

transverse gib, and lugs arranged to extend through the holes of the upper yoke arm and into the upper holes of the draw bar butt; of a locking block insertible vertically through 5 the bottom of the hood, said block having a front shoulder engaging the front shoulder of the draw bar, said block having lugs arranged to extend through the rivet holes of

the lower arm of the yoke and into the lower rivet holes of the draw bar butt; and 10 means for holding the locking block in operative position.

In witness that I claim the foregoing I have hereunto subscribed my name this 4 day of Aug. 1917.

JOSEPH HARRIS.
